[57] CLAIM

The ornamental design for combined eyeglasses and
shielding cassette therefor, as shown and described.

DESCRIPTION

FIG. 1 is a front elevational view of combined eyeglasses and shielding cassette therefor, showing my new design;

FIG. 2 is a top plan view thereof;

FIG. 3 is a front elevational view of the eyeglass frame,
the shielding cassette has been omitted for ease of illustration;

FIG. 4 is a top plan view thereof;

FIG. 5 is a front elevational view of the shielding cassette,
the eyeglass frame has been omitted for ease of illustration;

FIG. 6 is a top plan view thereof;

FIG. 7 is a rear elevational view thereof;

FIG. 8 is a side view of the design shown in FIG. 1.
